Wm Wallace White
ATTY.

UNITED STATES PATENT OFFICE.

GEORGE HUGH BEATTIE LOCKETT, OF GISBORNE, NEW ZEALAND.

ARTIFICIAL TOOTH.

1,398,560.

Specification of Letters Patent. Patented Nov. 29, 1921.

Application filed March 5, 1921. Serial No. 449,647.

To all whom it may concern:

Be it known that GEORGE HUGH BEATTIE LOCKETT, dentist, citizen of the British Empire, residing at 21 Carnarvon street, town 5 of Gisborne, in the Dominion of New Zealand, has invented certain new and useful Improvements in Artificial Teeth, of which the following is a specification.

This invention relates to artificial teeth 10 and its object is to provide an artificial tooth which is of universal use for gold or plate work, which is preferably adapted to backing, in which no checking is required, is interchangeable, easy to repair, is strengthened 15 for vulcanite work, and does not rock on the plate. In its applicable for any class of artificial tooth, flat back or shoulder tooth, whether the usual pins be baked in or soldered in, or are long pins or headed pins. 20 The object of the invention is effected by forming in the tooth a recess under cut or shaped in any pattern with pins secured therein inclined to or from each other for retention of cement and a cap preferably of 25 metal adapted to fit into the recess and over the pins enabling a wax pattern to be made without sticking to the tooth wherefrom the gold backing is cast integral with the cap. By these means there is perfect relationship 30 and connection between the cap and the recess in the tooth and the backing and there is no need for this tooth to be placed in a furnace or vulcanizer and no necessity for using precious metals in its manufacture. 35 The invention is illustrated on an enlarged scale in the accompanying drawings in which Figure 1 is a sectional elevation of the tooth in a vulcanite plate, Fig. 2 is a back elevation of the tooth showing the recess and 40 the pins therein, Fig. 3 is a sectional plan of the tooth through line *a*—*b* of Fig. 2 showing the inclination of the pins, Fig. 4 is a sectional elevation of the tooth showing the cap in position and the wax pattern over 45 same, Fig. 5 is a perspective plan of the cap, Fig. 6 is a sectional elevation of the tooth showing the gold backing and cap in position cemented to the tooth. Referring to these drawings the tooth (1) is formed with 50 a sharp cutting edge (2) and has the usual curved upper surface 3 at the back. A recess 10 is formed in the tooth (1) preferably by increasing the usual thickness of the tooth by the integral addition of a recessed 55 portion 5 to the tooth instead of forming the recess 10 in the body of the tooth which

would weaken it. This recess 10 is preferably of a depth of one fourth or one fifth of the thickness of the tooth. In the middle of the recess 10 there are secured to the tooth 60 preferably inclined headed pins 14 for vulcanite work as shown in Figs. 1, 2 and 3 and headless pins 6 for gold work as shown in Figs. 4 and 6. These pins are made headless so that a cap 8 see Fig. 5 may embrace 65 them as shown in Fig. 4, the edge 7 of the cap reaching near the bottom of the recess 10 and the body of the cap protruding out of the recess about half the thickness of the cap. A piece of wax 15 see Fig. 4 is pressed 70 to form a pattern over the back of the cap and of the tooth and up the curved portion 3 to the gingival margin or end 4. The wax pattern 15 holding the cap 8 is then removed and from it is cast the gold backing 75 16 see Fig. 6 having integral with it the cap 8 which projects out of the backing to the depth of the recess 10 in the tooth. The pins if not originally placed inclined in the tooth are now bent to incline and the tooth 80 is then cemented on in the usual way to the backing. It will be seen that by these means the backing of the tooth can be made with a flat back and sharp cutting edge 13, see Fig. 6 so that the bite of the opposing teeth can 85 when necessary pass behind this edge 13. The cap instead of having a closed back as shown in Fig. 4 may be open as the cast backing will form a back to it as seen in Fig. 6. 90

I claim:

1. An artificial tooth comprising a body portion, a recess formed on the back of said body portion, pins within said recess, secured to said body portion and a cap adapted to fit into said recess over said pins and protrude from said body portion substantially as and for the purposes set forth. 95

2. An artificial tooth consisting of a body portion, a recess formed on the back of said body portion, pins within said recess secured to said body portion and a backing having formed integral therewith a cap, said backing and cap being secured to the back of said body portion substantially as described. 100 105

In testimony whereof he has affixed his signature in presence of two witnesses.

GEORGE HUGH BEATTIE LOCKETT.

Witnesses:

ANDREW JOHN PARK,
YVONNE HARDY.
